(57) **CLAIM**

The ornamental design for a swim ring, as shown and described.

DESCRIPTION

FIG. 1 is a top, rear, right side perspective view of a swim ring, showing my new design;

FIG. 2 is a bottom, left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion 9 in FIG. 1;

FIG. 10 is an enlarged view of portion 10 in FIG. 1; and,

FIG. 11 is an enlarged view of portion 11 in FIG. 2.

The unevenly dashed broken lines surrounding details shown in FIGS. 1, 2 and 9-11 are for the purpose of annotating the enlarged views only and form no part of the claimed design.
